UNITED STATES PATENT OFFICE.

WILLIAM JASKIEWICZ, OF LAFAYETTE, COLORADO.

SAFETY DEVICE FOR ELEVATORS.

1,121,729.

Specification of Letters Patent. Patented Dec. 22, 1914.

Application filed April 6, 1914. Serial No. 829,879.

To all whom it may concern:

Be it known that I, WILLIAM JASKIEWICZ, a citizen of the United States, and residing at Lafayette, in the county of Boulder and 5 State of Colorado, have invented certain new and useful Improvements in Safety Devices for Elevators, of which the following is a specification.

This invention relates to certain new and 10 useful improvements in safety devices for elevators.

The primary object of this device is to provide a means that is readily mounted upon an elevator and whereby the breaking 15 of the hoisting cable therefor automatically releases a stationary locking device for the elevator car, thereby instantly stopping the elevator and preventing any injury to the contents thereof which would otherwise result 20 from the falling of the car.

A further object of the device is to provide a simple and inexpensive means readily attached to an elevator car and shaft and adapted for coöperating to insure against 25 the dropping of the car within the shaft upon the accidental severance of the car hoisting means.

A still further object is to provide a rack means within the shaft and meshing pinions 30 therefor carried by revoluble shafts upon the car, and automatic means carried by the latter for locking such pinion shafts against rotation whenever the hoisting cable becomes slack or broken.

35 With these general objects in view and others that will appear as the nature of the invention is better understood, the same consists in the novel combination and arrangement of parts hereinafter fully described, illustrated in the accompanying drawings, and pointed out in the appended claims.

In the drawings forming a part of this application and in which like designating 45 characters refer to corresponding parts throughout the several views:—Figure 1 is a vertical longitudinal sectional view taken through an elevator shaft and a car positioned therein, illustrating the invention installed thereon. Fig. 2 is a similar sectional view taken upon a plane at right angles to the line of section of Fig. 1. Fig. 3 is a detail perspective view of one of the locking levers and its guide rod as employed upon 50 the car. Fig. 4 is a horizontal transverse

sectional view taken upon the line 4—4 of Fig. 1, looking in the direction of the arrows, and, Fig. 5 is a similar sectional view taken upon line 5—5 of Fig. 1, looking in the direction of the arrows, parts of the 60 same being broken away.

Referring more in detail to the drawings, the elevator shaft 10 is illustrated with the car 11 mounted thereon and adapted for vertical movement, being propelled upwardly by means of the usual hoisting cable 12.

Racks 13 are provided oppositely positioned within the shaft and extending from the top to the bottom thereof, the said racks 70 being provided with opposite side teeth 14.

The car bottom 15 is provided on its under side with parallel brackets 16 having the revoluble shafts 17 journaled therein and positioned transversely of the car, and 75 each provided upon its opposite ends with pinions 18 having constant engagement with the teeth 14 of the racks and moving thereon during the travel of the car in either direction and whereby the shafts 17 are caused 80 to revolve at all times while the car is moving.

Two angular levers 19 are pivotally mounted upon the pin 20 to the car bottom and are provided with an expulsion spring 85 21 positioned between their longer arms 22 while the free ends of said arms are turned over forming a loop 23 for the reception of a guide rod 24 carried by the car bottom and whereby the pivotal movement of the 90 arms is guided by the said rod.

A cord 25 is threaded through the connecting links 26 of the supporting cable 12 at the top of the car and has its opposite ends extending downwardly along the opposite sides of the car and running over rollers 27 oppositely positioned adjacent the car bottom and opposite top rollers 27', while the free ends of the cord are secured to the oppositely-projecting short arm 28 of the members 19. Such connection of the cord with said short arms 26 is such that with the usual weight upon the supporting cable 12, the cord 25 will forcibly hold the arms 28 apart and thereby retain the long arms 22 in their innermost positions and consequently press the expulsion spring 21 therebetween.

With the cord 25 retaining the spring 21 compressed, the arm members 22 are out of 110

engagement with the star wheel 29 rigidly secured upon the shaft 17, and oppositely positioned, while upon a releasing of the cord 25 as by a severing or slackening of the cable 12, the short ends 28 are released whereupon the tension of the spring 21 forces the long ends 22 outwardly as guided by the rod 24 and into locking engagement with the opposite star wheels 29.

10 The complete operation of the device will be at once apparent from the above detailed description, in that the arms 22 are normally held out of engagement with the star wheels 29 by means of the cord 25 during the usual movements of the car in its travel, and at all of which times the shafts 17 and their star wheels are caused to revolve by means of the engagement of the pinions 18 upon the racks 14 and it will be 15 evident upon the breaking of the hoisting cable 12, the cord 25 will be relaxed, allowing the spring 21 to operate and engage the arms 22 with the star wheels 29, and effecting an immediate stopping of the car as 20 well as a locking of the same in such position. The car may then be released for further movement only upon forcing inwardly the arms 22 out of engagement with the star wheels 29.

25 30 While the form of the invention herein shown and described is what is believed to be a preferable embodiment thereof, it is nevertheless to be understood that various forms and modifications may be had without departing from the spirit and scope of the invention as claimed.

What is claimed as new is:—

1. A device of the class described, comprising in combination with an elevator shaft and a car movable therein, of oppositely positioned double racks vertically mounted within the elevator shaft, journaled shafts carried by said car, oppositely positioned pinions upon the ends of each of 40 said shafts and adapted for traveling engagement with said racks, centrally positioned star wheels secured to said shafts, angular locking levers pivoted to said car and each having long and short portions, 45 expansion means between the longer portions of said levers adapted for separating the same and engaging them with said wheels, a cord engaging the hoisting cable of the elevator and connected to the outwardly projecting shorter arms of said levers and adapted for inwardly positioning

the long portions thereof with said resilient means under compression.

2. A device of the class described, comprising in combination with an elevator shaft, a car movable therein, of double racks mounted in said shaft, opposite shafts journaled upon the bottom of said car, pinions upon the opposite ends of said shafts in meshing engagement with said racks, central star wheels oppositely positioned and secured to said revoluble shafts, angular levers each having a long and a short arm, a pivot post upon which both of said levers are mounted, an arcuate guide rod upon the bottom of the car, the long arms of said levers being overturned forming loops for sliding engagement with said rod, an expansion spring between said long arms, a cord engaging the elevator hoisting cable and having its free ends secured to the short arms of said levers and adapted for normally positioning inwardly the long arms thereof with said spring under compression therebetween.

3. A device of the class described, comprising in combination with an elevator shaft, a car movable therein, of double racks mounted in said shaft, opposite shafts journaled upon the bottom of said car, pinions upon the opposite ends of said shafts in meshing engagement with said racks, central star wheels oppositely positioned and secured to said revoluble shafts, angular levers each having a long and a short arm, a pivot post upon which both of said levers are mounted, an arcuate guide rod upon the bottom of the car, the long arms of said levers being overturned forming loops for sliding engagement with said rod, an expansion spring between said long arms, a cord engaging the elevator hoisting cable and having its free ends secured to the short arms of said levers and adapted for normally positioning inwardly the long arms thereof with said spring under compression therebetween, the said levers adapted for automatic engagement with said star wheels upon a severing of said cable and thereby locking the car against movement.

In testimony whereof I affix my signature in presence of two witnesses.

WILLIAM JASKIEWICZ.
